UNITED STATES PATENT OFFICE.

GEORGE H. WILLIAMS, OF BOSTON, MASSACHUSETTS, ASSIGNOR, BY MESNE ASSIGNMENTS, TO NEVADA MANUFACTURING COMPANY, OF RENO, NEVADA, A CORPORATION OF NEVADA.

LAUNDRY CLIP OR TAG.

1,292,198.

Specification of Letters Patent.

Patented Jan. 21, 1919.

Application filed January 6, 1915. Serial No. 859.

To all whom it may concern:

Be it known that I, GEORGE H. WILLIAMS, a citizen of the United States, and a resident of Dorchester, in the city of Boston, 5 county of Suffolk, and State of Massachusetts, have invented an Improvement in Laundry Clips or Tags, of which the following description, in connection with the accompanying drawings, is a specification, like 10 characters on the drawings representing like parts.

This invention relates to tags and clips, and is more especially, though not exclusively, concerned with a clip intended as an 15 identification tag to be secured to the edge of a garment or other article which is to be laundered or cleansed.

My invention will be best understood by reference to the following specification, 20 when taken in connection with the accompanying drawings of one specific embodiment thereof, while its scope will be more particularly pointed out in the appended claims.

25 In the drawings:

Figure 1 is a perspective view of a completed clip or tag embodying my invention the same being shown for the purpose of clearness much larger than the tags are 30 usually made in practice;

Fig. 2 is a perspective view of the metallic body as it appears when ready to receive the envelope or covering;

Fig. 3 is a perspective view of the body 35 and envelope partially assembled, with two opposite marginal portions of the envelope folded over two opposite edges of the body; and

Fig. 4 is a perspective view of the body 40 and envelope completely assembled and ready to be formed into a finished tag or clip, by being bent into the U-shaped form shown in Fig. 1.

Referring to the drawings, and to the 45 embodiment of my invention which I have selected for illustration, I have there shown a clip or tag comprising a body 5, preferably formed of sheet metal which may be readily cut, punched and bent into the desired form. In order to provide a suitable marking surface upon which the identification mark or marks may be placed, and further, as a means for protecting the garment or other article from injury due to 50 corrosion of the metallic body, or cutting

or abrasion by the sharp edges of the body, the latter is herein provided with an envelope 6, which covers the outer surface of the body, a large part of its inner surfaces, and all of its marginal edges, whereby the latter 60 are prevented from injuring the garment. The importance of covering all the edges of the body will be readily appreciated when it is understood that the metallic blanks for the body are usually produced from sheet 65 metal which is sheared, and the shearing is apt to produce sharp burs which, if not covered, would be very apt to cut the garment, especially where the clip engages the edge of the garment. To this end, therefore, the envelope overlaps all of the edges 70 of the body, and constitutes an effective means for preventing such injury to the garment.

The preferred material for the envelope 75 is suitable fabric, such for example as cotton cloth, the area of the cloth blank being great enough so that it can overlap all edges of the metal blank. The latter may be of any other suitable form, but herein is rec- 80 tangular, and in practice is formed by being cut from a strip of appropriate metal in such a manner that the dividing cut forms two chamfered or beveled corners 7-7 at one end of the blank, and a pair of spurs 85 8-8 at the other end of the blank, the metal for the spurs of one blank being taken from the beveled or chamfered corners of the next succeeding blank, as will be readily apparent. These projecting spurs are then bent 90 as shown in Fig. 2, whereby these corners also are chamfered or beveled. By chamfering the corners in this manner, they are much less likely to injure the garment than if they were left square. The spurs formed 95 at two corners of the blank are, or may be, employed for a purpose which will presently appear.

The blank is also provided with other spurs which, in the completed tag or clip 100 appear on the inner faces thereof, and are intended to enter the garment from opposite surfaces thereof, and securely fasten the tag thereto, so that it may serve as a means of identification of the garment. These spurs 105 may be of any suitable number and arrangement, but I have herein shown two pairs 9-9 and 10-10, of generally triangular shape produced by the use of dies or tools which are forced through the blank in such 110

a manner as to leave the spurs upstanding at practically right angles to the plane of the blank.

The blank may be provided with suitable means to secure the envelope thereto, as for example, one or more, herein two, pairs of tongues 11-11 and 12-12, formed by the use of dies or tools forced through the blank in such a manner as to leave the tongues 10 in an upstanding position practically at right angles to the plane of the blank. These tongues are intended to be later bent backward, so as to overlie portions of the blank and securely hold the envelope in its 15 intended position on the blank.

In assembling the metallic blank and the fabric blank which is to constitute the envelope, the metallic blank is placed spurs upward upon the fabric blank. The two longitudinal edges of the latter are then folded inwardly as shown in Fig. 3, whereby they are caused to overlap and cover the two opposite longitudinal edges of the metallic blank. In so doing, the spurs 8 are caused 20 to enter the folded over marginal portions of the fabric, whereby the two blanks are effectually positioned with relation to each other, and slipping and consequent disarrangement of the blanks is prevented during 25 the subsequent operations.

The next step is to fold the two remaining opposite marginal portions of the cloth blank inwardly toward each other until they overlap and rest upon the first marginal 30 portions. In so doing, the spurs 9-9 and 10-10 are caused to pierce the cloth blank, and to project a substantial distance beyond the face of the latter, so that they may be later utilized as a means for securing the 35 tag to the garment. The spurs 8-8, however, by preference are previously bent inwardly and downwardly upon the relatively narrow marginal portions of the cloth blank which were first folded down upon the metallic blank, and they are consequently covered by one of the relatively wider marginal 40 portions. The latter are securely held in their intended positions, as shown in Fig. 4, by bending the tongues 11-11 and 12-12 45 in an outward and downward direction, whereby they are caused to overlap opposite marginal edges of the cloth blank, and effectually prevent its accidental removal from the metallic blank.

50 Finally, the completely assembled blanks are bent transversely thereof along the central portion to form a generally U-shaped clip, as shown in Fig. 1, provided with two arms having opposed supports. It will 55 now be evident that the clip may be applied to the edge of the garment or other article to be laundried or cleansed, and when subjected to pressure upon opposite sides thereof in a proper manner, will be squeezed and 60 its spurs caused to penetrate the garment and

securely hold the clip or tag in place. The cloth covering or envelope may be marked with the identification characters at any desired time, either before, after, or while being attached to the garment.

While I have herein shown and described one specific embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire by Letters Patent to procure is:-

1. A tag or clip comprising a body of flexible sheet metal adapted to be pressed in U form over the edge of a garment and an exterior covering of textile fabric enveloping and covering all the marginal edges of said body.

2. A tag or clip comprising a substantially U shaped metallic body and a fabric covering over one side thereof having marginal portions folded over the various edges thereof and completely covering the same.

3. A tag or clip comprising a quadrilateral body of flexible metal and a fabric covering applied to said body having marginal portions folded over and covering two opposed edges of the body and other marginal portions folded over and covering the other edges said latter portions being secured in place overlying said first portions.

4. A tag or clip as defined in claim 2 wherein the marginal portions of the covering are secured by spurs on the body.

5. A tag or clip comprising a quadrilateral body of flexible metal and a fabric envelope having portions extending over and covering opposite marginal edges of the body, said envelope having portions extending past the other edges, folded over and completely inclosing the same.

6. A tag or clip comprising a substantially U-shaped metallic body, and an envelope therefor having a pair of opposite marginal portions folded over one pair of edges of said body and another pair of opposite marginal portions folded over another pair of opposite edges of said body, said body being provided with two or more integral tongues to secure the second-mentioned pair of marginal portions to said body.

7. A tag or clip comprising a substantially U-shaped metallic body, and an envelope therefor having a pair of opposite marginal portions folded over one pair of edges of said body and another pair of op-

posite marginal portions folded over another pair of opposite edges of said body, said body being provided with spurs extending through the first-mentioned marginal portions, and two or more tongues to secure the second-mentioned marginal portions in place upon the first.

8. A tag or clip comprising a substantially U-shaped metallic body, and an envelope therefor having a pair of opposite marginal portions folded over one pair of edges of said body and another pair of opposite marginal portions folded over another pair of

opposite edges of said body, said body being provided with means to secure the first- 15 mentioned marginal portions to said body, and means to secure the second-mentioned portions to said body.

In testimony whereof, I have signed my name to this specification in the presence 20 of two subscribing witnesses.

GEORGE H. WILLIAMS.
